UNITED STATES PATENT OFFICE.

JOHN B. DRAPER, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed March 22, 1924. Serial No. 701,044.

This invention relates to machine switching telephone systems and more particularly, to such systems wherein the trunk circuits between offices are accessible at more than one point.

Heretofore in systems of this general type, it has been customary to render the trunk circuit busy at all points of access when it is seized at any point, and to remove the busy condition at the point of seizure long enough to permit the mechanical switches to release and free the trunk, rendering it busy again thereafter at the point of original seizure until the trunk is fully restored to normal. During the unguarded interval which thus occurs, it sometimes happens that the trunk is again seized by another mechanical switch which happens to be in the trunk hunting position.

The object of this invention is to permit the switching mechanism to release while at the same time preventing the trunk from being again seized until it is fully restored to normal.

In accordance with this invention means are provided in the trunk to cooperate with the switching mechanism seizing the trunk whereby the trunk is caused to test busy, the means aforesaid allowing the switching mechanism to regulate its own release, but causing the trunk to test busy again instantly thereafter and to remain busy until it is restored to normal. More specifically, a relay is retained inoperative due to a circuit condition impressed upon the trunk test terminal by the switching mechanism the circuit condition changing the instant switching mechanism releases, whereby the relay previously held inoperative is allowed to operate and cause the trunk to again test busy, the unguarded interval at the test terminal being reduced to the time required to operate the relay in question, which in practice, is a negligible length of time, virtually eliminating the possibility of a double trunk seizure.

In the drawing comprising but a single sheet, the invention is diagrammatically shown applied to a toll telephone system employing mechanical switches. The designation DTC indicates a distant toll center having access over a toll line TL to the repeater R, thence by way of the toll selector switch (T) to the trunk circuit. At the left is shown a toll cord TC at the toll switchboard (T. S. B.)

of a second toll center, the trunk circuit appearing before the toll operator at the second toll center in a trunk jack. The trunk extends ST to a neighboring office wherein connections are established by means of mechanical switches, the trunk terminating thereat in an incoming selector IS. The remaining switches required to build up a typical connection to the called station 24 are a transmission selector (TS), a third selector (S-3) and a connector (C).

It is believed that the invention will be more readily understood from the detailed description of the progress of a typical call from either the distant toll center DTC or the second toll center which follows:

CALL FROM DISTANT TOLL CENTER.

Initiating call.

When the distant toll center DTC desires to establish a connection to the called station 24 the dial 1 at the distant toll center is operated and released in accordance with the office code of the second toll center and the call progresses over the toll line TL to operate the repeater R which may be of any of the well-known types, commonly used in the art. The toll selector (T) functions in a manner (not shown) to extend the connection by way of the brushes 4, 5 and 6 and the terminals 7, 8 and 9 to the switching trunk ST. With the brush 6 resting on the terminal 9 a circuit is closed to operate relay 49 as follows: battery, winding of relay 49, 99, 98, 9, 6, to ground. Relay 49 operated locks in series with relay 45 to ground at armature 75 of relay 40 and connects battery at its armature 100 to the test sleeve 38 of the jack 35 and all multiples thereof at the toll switchboard TSB, causing the trunk circuit to test busy at the toll switchboard. The relay 45 does not operate at this time because it is short-circuited by the ground at the test brush 6 of the toll selector (T).

The dial 1 at the distant toll center DTC is now operated and released in accordance with the various digits comprising the number of the called line 24 and the relay 2 responds to the impulses produced by the dial 1.

The bridge through the winding of the relay 3 is opened each time the relay 2 operates, thus repeating the impulses by way of the

- toll selector (T) and the switching trunk ST to the selector switches IS, TS, S-3 and the connector C in succession, whereby the connection is extended to the called line 24.
- 5 The switches IS, TS, S-3 and the connector C may be of any well known type, but for convenience it will be assumed that these switches are of the Strowger type so well known in the art, in which case, the connection will be established as described in the patent to Ray Stokely, 1,553,337 dated Sept. 15, 1925. Signaling and supervision will occur and conversation will take place substantially in the manner disclosed and described in the application cited.

Disconnection.

When disconnection takes place at the distant toll center DTC, the toll selector (T) releases in the manner well-known in the art and the brushes 4, 5 and 6 are restored to normal removing the ground from the test terminal 9 of the trunk circuit. The moment ground is removed from the test terminal 9 relay 45 operates in series with the winding of relay 49. Relay 45 operated connects solid ground to the test terminal 9 by way of 98, 99 and 97, thus providing a busy test condition at the test terminal 9 to prevent any other selector switch in the trunk hunting position from seizing this trunk. So long as the receiver is removed from the switchhook at the station of the called line 24, the supervisory relay 17 will remain operated retaining the relay 15 operated over an obvious circuit. So long as relay 15 remains operated the battery and ground supplied to the switching trunk ST through the windings of relay 16 will be disconnected from the trunk circuit.

40 The operation of relay 45 connected the winding of relay 40 in bridge across the conductors of the switching trunk ST over the following circuit: brush 10, switching trunk ST, 87, 96, 95, 94, winding of relay 40, 83, switching trunk ST to brush 11. As long as relay 15 remains operated relay 40 will not operate, hence, relays 49 and 45 will remain locked in series to ground at the armature 75 of relay 40. When the receiver is replaced on the switchhook at the station of the called line 24, relays 17 and 15 will release in sequence and battery and ground will be again connected by way of the windings of relay 16 and the incoming selector IS to the switching trunk ST. Relay 40 will operate in series with the windings of relay 16, opening at 75 the locking circuit previously traced for relays 45 and 49 which release. Relay 49 released, removes the busy condition from the test sleeve 38 of the jack 35 and all multiples thereof at the toll switchboard TSB and relay 45 released removes ground at its contact 97 from the test terminal 9 causing the trunk circuit to test idle at the multiple bank of the toll selector (T). Relay 45 released, also opens at

94 and 95 the bridge previously established through the winding of relay 40 across the switching trunk ST, releasing relay 40 and restoring the circuit to normal.

CALL FROM SECOND TOLL CENTER.

Initiating call.

When it is desired to establish a connection with the toll line 24 from the toll switchboard TSB, the plug 34 of the toll cord TC is inserted in the jack 35 or any multiple thereof of the trunk circuit at the toll switchboard TSB. Relay 46 now operates over a circuit as follows: battery, winding of relay 33, 38, 80 winding of relay 46 to ground. A circuit is likewise established to operate relay 51 as follows: battery, resistance 53, left winding of relay 51, 54, 55, 37, 59, 58, winding of relay 31, 60, 61, 36, 56, 57, winding of relay 47 to ground. Relays 31 and 47 do not operate at this time due to the high resistance of the winding of relay 51 and of the resistance 53 in series with them. Relay 46 operated closes at its armature 103 an obvious circuit to operate relay 14. Relay 14 operated, connects solid ground by way of its armature 98 to the test terminal 9 of the toll selector (T) at the multiple bank causing the trunk circuit to test busy to all toll selector switches. Relay 51 operated locks through its right winding over the following circuit: ground in the incoming selector IS (not shown) switching trunk ST, 87, 96, 86, winding of relay 50, 85, 84, right winding of relay 51, 79, winding of relay 40, 83, switching trunk ST to battery (not shown) in the incoming selector IS. Relay 40 operates over the circuit previously traced in series with relay 51, but relay 50 which is polarized does not operate at this time.

Dialing the number.

The dial 25 is now operated and released in accordance with the various digits comprising the number of the called line 24. When the dial is operated contact springs 28 and 29 of the dial 25 are closed, operating relay 30 over an obvious circuit. Relay 30 operated substitutes a path by way of the impulse springs 26 and 27 of the dial 25 for the winding of relay 31, normally bridged across the toll cord TC. The series circuit previously traced through the left hand winding of relay 51, winding of relay 31, winding of relay 47 is opened, but relay 51 remains locked up through its right hand winding in series with relays 40 and 50. A circuit is now closed to operate the impulse relay 47 as follows: battery, impulse springs 27 and 26 of the dial 25, 62, 61, 36, 56, 57, winding of impulse relay 47 to ground. Relay 47 operated closes at 71 a path to short circuit the right winding of relay 51 and the winding of relay 50 releasing relay 51. Relay 40 is now bridged

directly across the conductors of the switching trunk ST over the following circuit: switching trunk ST, 83, winding of relay 40, 79, 71, 87 to the switching trunk ST. The 5 impulse relay 47 operated also closes a circuit to operate relay 42 as follows: battery, armature 63 of relay 44, 64, resistance 65, 66, 67, 68, 69, winding of relay 42, 70 to ground. Relay 42 operated closes a circuit to operate 10 relay 48 as follows: battery, winding of relay 48, 72, 73, 63 to ground. Relay 48 operated locks by way of 78 and 74 to ground at 63, thus providing a substitute path to retain 15 relay 42 operated after the impulse relay 47 releases as follows: battery, armature 63 of relay 44, 64, resistance 65, 69, winding of relay 42, 70 to ground. Relay 42 operated connects the interrupter 41 in series with the winding of the relay 52 and relay 52 operates 20 and releases under control of the interrupter 41, but performs no useful function at this time.

The impulse relay 47 operates each time the impulse springs 26 and 27 of the dial are 25 closed and releases each time these impulse springs are opened. The impulse circuit for setting the incoming selector IS is controlled at the armature 71 of the impulse relay 47. Hence, the incoming selector IS is set under 30 control of the impulse relay 47. The relay 30 in the toll cord TC is designed to be slow to release so that it will not release immediately at the end of each train of impulses corresponding to a particular digit, hence, 35 the circuit including the winding of the impulse relay 47 and the impulse springs 26 and 27 of the dial 25 will not be permanently opened until all the digits comprising the number of the called line have been dialed. 40 The various selector switches IS, TS, S—3 and the connector C will be set in accordance with the digits dialed and the connection will be established with the called line which we will assume to be the line 24.

45 *Called line busy.*

Assuming the called line 24 is busy, the battery and ground supplied through the windings of the relay 16 of the transmission 50 selector TS will remain connected to the circuit (in the manner shown in the drawing) after dialing is completed. With the dial 25 in the normal position, contact springs 28 and 29 will be separated and after a reasonable 55 interval of time, relay 30 will release, reconnecting the winding of relay 31 across the springs 36 and 37 of the jack 35. The left hand winding of relay 51, the winding of relay 31 and the winding of relay 47 will once more be connected in series over the circuit 60 previously traced but relays 31 and 47 will not operate, due to the high resistance of the left hand winding of relay 51 and of the resistance 53 in series with them. Relay 51 operates 65 through its left hand winding in

series with the windings of relays 31 and 47 and establishes a bridge across the conductors of the switching trunk ST through the winding of relay 50 over the following circuit: brush 10 of the selector IS, switching trunk 70 ST, 87, 96, 86 winding of relay 50, 85, 84, right hand winding of relay 51, 79, winding of relay 40, 83, switching trunk ST to brush 11 of the selector IS. The relay 50 is polarized and will not operate so long as battery 75 through the right hand winding of relay 16 is connected to the terminal 13 of the selector IS. Relay 42 which was operated and locked up during the dialing period connected the interrupter 41 in series with the winding of 80 relay 52 which operates and releases under control of the interrupter 41. Each time relay 52 operates battery is connected to its armature 82, thus short circuiting resistance 53 in series with the left hand winding of relay 85 51. Relay 31 will operate under this condition thus closing an obvious circuit to light the supervisory lamp 32 indicating to the operator at the toll switchboard that the called line is busy. 90

Called line seized.

Assuming, however, that the called line is idle, it will be seized by the connector C and relay 104 will be released and cause relay 105 95 to be operated to ground on the back contact of relay 106 to reverse the position of the battery and ground supplied over the conductors of the switching trunk ST through the windings of relay 16, thus reversing the direction 100 of the current flowing over the trunk conductors. A complete description of the method of reversing the position of the battery and ground through the windings of relay 16 is given in the patent to Ray Stokely, 1,553,337 105 dated Sept. 15, 1925. When relay 30 releases in the manner previously described under "called line busy" relay 51 will reoperate and relay 47 will release, thus establishing the bridge through the windings of relays 40 and 110 50 and the left hand winding of relay 51 in series across the conductors of the switching trunk ST. Relay 50 which is polarized now operates under control of the reversed battery and ground supplied through the windings 115 of relay 16 and closes an obvious circuit to operate relay 39. Relay 39 operated, locks by way of 76 and its armature 91; opens at 70 the circuit through the winding of relay 42 which releases; extends by way of its 120 armatures 101 and 102 and contacts 56 and 55 the toll cord circuit TC to the switching trunk ST and the called line 24. The release of relay 42 closes a circuit to operate relay 44 as follows: battery, winding of relay 44, 77, 72, 78, 74, 63 to ground. The called station 24 is signaled and responds in a manner not shown but which is fully described in the art cited, closing an obvious 125 circuit, to operate relay 17 which in turn 130

operates relay 15 over an obvious circuit thus disconnecting relay 16 from the switching trunk. Relays 40 and 50 now release. Relay 40 released, provides a locking path for relays 48 and 44 to prevent them from releasing when relay 46 releases as hereinafter described. This circuit is traced as follows: for relay 48, battery, winding of relay 48, 78, 74, 92, 93, 75 to ground; for relay 44, battery, winding of relay 44, 77, 72, 78, 74, 92, 93, 75 to ground.

Disconnect.

Assuming that the called station 24 disconnects before the toll cord TC is removed from the jack 35 at the toll switchboard TSB, relays 17 and 15 release in sequence reconnecting battery and ground through the windings of relay 16 to the switching trunk ST. A circuit is now closed to operate relay 31 as follows: battery, right hand winding of relay 16, 13, 11, 101, 56, 36, 61, 60, winding of relay 31, 58, 59, 37, 55, 102, 10, 12, left hand winding of relay 16 to ground. Relay 31 operated, lights the supervisory lamp 32 as a disconnect signal to the toll operator. When the plug 34 of the toll cord TC is removed from the jack 35, relay 46, releases. A circuit is now closed to supply a busy condition to the jack sleeve 38 until the trunk circuit is restored to normal as follows: battery, armature 63 of relay 44, 88, resistance 89, 90 to the jack sleeve 38. Relay 40 is now bridged across the switching trunk ST over the following circuit: brush 10, switching trunk ST, 87, 96, 79, winding of relay 40, 83, switching trunk ST to brush 11. Relay 40 operates in series with the windings of relay 16, thus opening at 75 the locking circuits for relays 14, 44 and 48 which release. The release of relay 48 opens at 76 the locking circuit for relay 39 which releases. The release of relay 44 opens at 79 the bridge across the trunk through the winding of relay 40 which releases, thus restoring the circuit to normal. It is evident from this description that a busy test condition is retained at the test terminal 9 and the jack sleeve 38 until the trunk circuit is fully restored to normal.

Assuming that the toll operator removes the plug 34 of the toll cord TC from the jack 35 before the called line 24 disconnects, relay 46 will release and the busy condition will be removed from the jack sleeve 38 during the releasing time of relay 46. Relay 46 released, closes at its armature 90 a substitute path to provide a busy condition at the jack sleeve 38 until the circuit is restored to normal as hereinafter described. Relay 14 which was operated under control of relay 46 will not release at this time as it is locked up by way of 92, 93 and 75 to ground under control of relay 40 which is not operated at this time. Relay 40 is now bridged across the conductors of the switching trunk over the following cir-

cuit: brush 10 of the selector IS, switching trunk ST, 87, 96, 79, winding of relay 40, 83, switching trunk ST to brush 11 of the selector IS. As long as the called station remains on the line, relays 17 and 15 will remain operated and battery and ground through the windings of relay 16 will be removed from the conductors of the switching trunk ST, hence relay 40 will not operate and the trunk circuit will continue to test busy at the test terminal 9 and the jack sleeve 38, thus preventing the re-seizure of the trunk circuit.

When the receiver is placed on the switchhook at the called station 24, relays 17 and 15 release in sequence and battery and ground through the windings of relay 16 are reconnected to the conductors of the switching trunk ST. Relay 40 is now operated in series with relay 16 opening at 75 the locking circuits for relays 14, 44 and 48 which release. The release of relay 48 opens at 76 the locking circuit for relay 39 which releases. The release of relay 44 opens at 79 the bridge circuit through the winding of relay 40 which releases and restores the circuit to normal.

All trunks busy.

Assuming that during dialing the incoming selector IS encounters an all trunks busy condition, the circuit through the winding of relay 40 will be momentarily opened (in a manner not shown) and relay 40 will release. Relay 40 released, connects a ground by way of 75, 67, 66 and 69 to the winding of relay 42, thus short-circuiting the relay, which releases. The release of relay 42 closes a circuit to operate relay 44 as follows: battery, winding of relay 44, 77, 72, 78, 74, 63 to ground. Relay 44 operated, connects the interrupter 43 in series with the winding of relay 52 which operates and releases under control of the interrupter. When relay 30 releases at the end of the dialing period, relays 47 and 31 are once more connected in series with the left winding of relay 51. Under this condition, each time relay 52 operates and short-circuits resistance 53 in series with the left winding of relay 51 relay 31 is operated, and the supervisory lamp 32 is lighted, thus supplying a distinctive flashing signal to the toll operator, indicating that all trunks are busy.

It should be observed that the flashing signal provided under control of the interrupter 41 when the called line is busy is different from that produced under control of the interrupter 43 when all trunks are busy so that no confusion between the signals need occur.

What is claimed is:

1. In a telephone system, a telephone line, a manual switch, a mechanical switch, means for linking each switch to the line, means individual to each switch for imposing a busy condition directly upon the test terminal or sleeve of the line at the linking point used, means included in the line and controlled by

the particular switch used for imposing a busy condition upon the test terminal or sleeve of the line at the other linking point, means included in the line operated when the 5 switch is disassociated therefrom for substituting a self-imposed busy condition upon the test terminal or sleeve for the busy condition previously supplied by the switch while maintaining the busy condition upon the test 10 terminal or sleeve at the other linking point, and means for removing the busy condition from each test terminal or sleeve when the line is again ready for use.

2. In a telephone system, a mechanical 15 switch, a trunk circuit accessible thereto, means included in the mechanical switch for imposing a busy condition upon the test terminal of the trunk when seized by the switch, and relay means included in the trunk 20 circuit and energized by the mechanical switch in releasing for maintaining a busy condition upon the test terminal of the trunk until said trunk is restored to normal.

3. In a telephone exchange system, a mechanical 25 switch, a cord circuit, a trunk circuit directly accessible to either the switch or the cord circuit, means included in the mechanical switch for imposing a busy condition upon the test terminal of the trunk when seized by the switch, and means included in the trunk 30 circuit and set by the mechanical switch in releasing for maintaining a busy condition upon the test terminal of the trunk until it is restored to normal.

35 4. In a telephone exchange system, a mechanical switch, a cord circuit, a trunk circuit directly accessible to either the switch or the cord circuit, means included in the mechanical switch for imposing a busy condition at the 40 switch bank upon the test terminal of the trunk when seized by the switch, and means included in the trunk circuit and set by the mechanical switch in releasing for maintaining a busy condition upon the test terminal of the trunk at the switchbank until the trunk 45 is restored to normal.

5. In a telephone exchange system, a cord circuit, a mechanical switch, a trunk circuit directly accessible to either the switch or the 50 cord circuit, means controlled by the cord circuit when used for placing a busy condition upon every test terminal or sleeve of the trunk, means included in the mechanical switch for imposing a busy condition at the 55 switch bank upon the test terminal of the trunk when seized by the switch, and means included in the trunk circuit and set by the mechanical switch in releasing for maintaining a busy condition upon the test terminal of the trunk at the 60 switch bank until the trunk is restored to normal.

6. In a telephone exchange system, a trunk circuit accessible to both manual and mechanical switching devices, means controlled by 65 the manual switching device when used for

placing a busy condition upon the test terminal or sleeve of the trunk at each point of access, means included in the mechanical switch for directly imposing a busy condition upon the test terminal of the trunk at the 70 point of mechanical switch access and indirectly imposing a busy condition upon the test terminal or sleeve of the trunk at the point of manual switch access, and means included in the trunk circuit and set by the 75 mechanical switch in releasing for maintaining a busy condition upon the test terminal or sleeve of the trunk at every point of access until the trunk is restored to normal.

7. In a telephone exchange system, a trunk 80 circuit directly accessible to both manual and mechanical switching devices, means controlled by the manual switching device when used for placing a busy condition upon the test terminal or sleeve of the trunk at each 85 point of access, means included in the mechanical switch for imposing a busy condition upon the test terminal of the trunk at the point of mechanical switch access, means operated by the mechanical switch for imposing 90 a busy condition upon the test terminal or sleeve of the trunk at the point of manual switch access until the trunk circuit is restored to normal, and means included in the trunk circuit and set by the mechanical switch in releasing for maintaining a busy condition upon the test terminal of the trunk at the point of mechanical switch access until the trunk circuit is restored to normal.

8. In a telephone exchange system, a trunk 100 circuit directly accessible to both manual and mechanical switching devices, means controlled by the manual switching device when used for placing a busy condition upon the test terminal or sleeve of the trunk at each 105 point of access, means included in the mechanical switch for imposing a busy condition upon the test terminal of the trunk at the point of mechanical switch access, means operated by the mechanical switch for imposing 110 a busy condition upon the test terminal or sleeve of the trunk at the point of manual switch access which busy condition is maintained thereon until the trunk is restored to normal, means included in the trunk circuit and set by the mechanical switch in releasing for maintaining a busy condition upon the test terminal of the trunk at the point of mechanical switch access until the 115 trunk circuit is restored to normal, and means for restoring the trunk circuit to normal.

9. In a telephone exchange system, a mechanical switch, a cord circuit, a trunk circuit accessible to the switch via a terminal bank and to the cord circuit via a trunk jack, means included in the cord circuit for imposing 120 a busy condition upon the sleeve of the trunk jack, means operated by the cord circuit for imposing a busy condition upon the test terminal at the terminal bank, means 125

65 130

included in the mechanical switch for imposing a busy condition upon the test terminal at the terminal bank, means operated by the mechanical switch for imposing a busy condition upon the sleeve of the trunk jack, and means included in the trunk circuit and set when the trunk is released by either the switch or cord for maintaining a busy condition upon the test terminal and jack sleeve of the trunk 10 until it is fully restored to normal.

10. In a telephone exchange system, a mechanical switch, a cord circuit, a trunk circuit accessible to the switch via a terminal bank and to the cord circuit via a trunk jack, 15 means included in the cord circuit for imposing a busy condition upon the sleeve of the trunk jack, means operated by the cord circuit for imposing a busy condition upon the test terminal at the terminal bank, means included in the mechanical switch for imposing a busy condition upon the test terminal at the terminal bank, means operated by the mechanical switch for imposing a busy condition upon the sleeve of the trunk jack, 20 25 means included in the trunk circuit set when the cord is removed from the trunk jack for maintaining the busy condition at the trunk jack sleeve and upon the test terminal at the terminal bank until the trunk is restored to 30 normal, and means included in the trunk circuit set when the mechanical switch releases for maintaining a busy condition upon the test terminal at the terminal bank and at the trunk jack sleeve until the trunk circuit 35 is restored to normal.

11. In a telephone exchange system, a mechanical switch, a cord circuit, a trunk circuit accessible to the switch via a terminal bank and to the cord circuit via a trunk jack, 40 means included in the cord circuit for imposing a busy condition upon the sleeve of the trunk jack, means operated by the cord circuit for imposing a busy condition upon the test terminal at the terminal bank, means included in the mechanical switch for imposing a busy condition upon the test terminal at the terminal bank, means operated by the mechanical switch for imposing a busy condition upon the sleeve of the trunk jack 45

means included in the trunk circuit set when the cord is removed from the trunk jack for maintaining a busy condition at the trunk jack sleeve and upon the test terminal at the terminal bank, means included in the trunk circuit set when the mechanical switch releases for maintaining a busy condition upon the test terminal at the terminal bank and at the trunk jack sleeve, and means for removing the busy condition from the jack sleeve and the test terminal when the circuit 60 is again available for use.

12. In a telephone exchange system, a trunk circuit provided with a jack at one point and a terminal bank at another, a cord circuit capable of being used with the trunk 65 via the jack, a mechanical switch capable of seizing the trunk at the terminal bank, means included in the cord circuit for imposing a busy condition upon the jack sleeve when the trunk is used thereat, means included in the trunk and controlled by the cord over the jack sleeve for imposing a busy condition upon the test terminal at the terminal bank, means included in the trunk circuit effective when the cord is removed from the jack for 70 substituting a self-imposed busy condition upon the jack sleeve while maintaining the busy condition upon the test terminal at the terminal bank until the trunk is again normal, means included in the mechanical switch effective when the trunk is seized for imposing a busy condition directly upon the test terminal at the terminal bank, means included in the trunk and controlled by the mechanical 75 switch over the test terminal for imposing a busy condition upon the jack sleeve, means included in the trunk circuit effective when the mechanical switch releases for substituting a self-imposed busy condition upon the test terminal at the terminal bank while 80 maintaining the busy condition upon the jack sleeve until the trunk is again normal, and means included in the trunk circuit for restoring the trunk circuit to normal.

In witness whereof, I hereunto subscribe my name this 19th day of March, A. D. 1924.

JOHN B. DRAPER.
